UNITED STATES PATENT OFFICE.

EDUARDO PERRONE, OF GLOVERSVILLE, NEW YORK.

DESIGN FOR A GLOVE.

58,627.

Specification for Design.

Patented Aug. 2, 1921.

Application filed February 10, 1919. Serial No. 276,237. Term of patent 14 years.

To all whom it may concern:

Be it known that I, EDUARDO PERRONE, a subject of Italy, residing at Gloversville, in the county of Fulton and State of New York, have invented a new, original, and ornamental Design for Gloves, of which the following is a specification, reference being had to the accompanying drawing, forming part thereof.

Figure 1 of the drawings is a view of the

palm-side of a glove embodying my design showing the finger and thumb portions in position as in use.

Fig. 2 is a plan view of the same with the thumb folded outwardly to substantially flat position.

I claim:

The ornamental design for a glove as shown.

EDUARDO PERRONE.
